UNITED STATES PATENT OFFICE.

VINCENT STONE, OF CHICAGO, ILLINOIS, ASSIGNOR TO MARSHALL FIELD & COMPANY,
OF CHICAGO, ILLINOIS, A CORPORATION OF ILLINOIS.

CLASP FOR HOLDING RIBBON-BOWS.

1,035,428.

Specification of Letters Patent. Patented Mar. 11, 1913.

Application filed December 2, 1911. Serial No. 663,572.

To all whom it may concern:

Be it known that I, VINCENT STONE, a citizen of the United States, residing at Chicago, in the county of Cook and State of Illinois, have invented certain new and useful Improvements in Clasps for Holding Ribbon-Bows, of which the following is a specification.

My invention relates in general to articles 10 of personal adornment and more particularly to a device for attaching a ribbon bow or other decorative article to the hair or clothing of a wearer.

The repeated tying and untying of hair 15 ribbons into bows, necessary when a portion of the ribbon itself serves as the attaching means, very soon so creases and wrinkles the ribbon as to render it unserviceable. Considerable time and skill is also 20 required to tie a ribbon into an attractive bow each time it is desired to use an ornamental bow.

The object of my invention is to provide 25 a simple device for conveniently holding and attaching to a wearer a previously formed ribbon bow or other article, my invention being more fully described herein-after with reference to the accompanying drawing, in which the same is illustrated 30 as embodied in a convenient and practical form and in which—

Figure 1 is a perspective view of my improved device with a ribbon bow in position thereon; Fig. 2 a cross sectional view 35 through the device and the inclosed portion of the bow; and Fig. 3 a perspective view of the device prior to the insertion therein of a bow.

The same reference characters are used 40 to designate the same parts in the several figures of the drawing.

Reference character A indicates a clasp 45 which may be conveniently stamped from sheet metal and then bent into the desired form for use. The clasp comprises a body portion or base *a* from the opposite edges of which project pairs of fingers which are preferably curved outwardly, upwardly and thence inwardly over the body portion. 50 In the form of my device shown in the drawing, two pairs of such fingers A' and A² are provided. The ends of the fingers in each pair terminate adjacent each other so as to leave a space for the insertion of 55 the knot of a ribbon bow. The ends of the

fingers are provided with inwardly inclined points *a'* and *a²*.

In order that the device may be conveniently secured to the hair or clothing of a wearer, a U-shaped fastening pin B is provided which is pivotally supported by a pair of ears *b* preferably formed integral with the body portion *a* and projecting from the opposite side thereof from the clasping fingers. Located adjacent the end of the body portion opposite to the ears *b* are two hooks *c*, which are also preferably formed integral with the body portion. The free ends of the pin B are adapted to be removably engaged with the hooks *c* after the pin has been inserted through the desired support therefor.

D indicates a bow made of ribbon, the central knot *d* of which is inserted between the fingers so as to be surrounded by them 75 with the points on the fingers pressed into the knot, in the manner shown in Fig. 2. It will, of course, be observed that my improved device may be used for holding other articles of ornament than ribbon 80 bows.

When a ribbon is to be supported by my improved device, it is first tied into a bow of the desired size and shape after which the knot of the bow is pressed between the ends 85 of the clasping fingers into the space formed by the fingers and body portion of the device. The device with the bow may then be readily attached by means of the pin B.

The material of which the device is 90 formed is preferably of sufficient resiliency to permit the fingers to be deflected sufficiently to permit the insertion and removal of the supported article.

From the foregoing description it will be 95 observed that I have invented an improved device which will permit the convenient attachment of a bow or an article of ornament to a wearer thereby rendering it unnecessary to tie and untie the bow each time 100 it is used.

I claim:

A device for holding a ribbon bow or the like and detachably supporting the same upon a wearer, comprising a body portion 105 made of sheet metal and spaced pairs of outwardly bowed resilient fingers formed integrally with the body portion and extending upwardly from the opposite edges thereof, the fingers in each pair terminating 110

adjacent and opposite each other to form a restricted space between each pair for the insertion of the bow and provided with inwardly and downwardly projecting pointed ends for engaging and preventing the removal of the inserted bow, and means for detachably securing the device to a wearer.

In testimony whereof, I have subscribed my name.

VINCENT STONE.
